UNITED STATES PATENT OFFICE.

CARL MERRITT CAMPBELL, OF HAGERSTOWN, MARYLAND.

FLOOR MAT.

Application filed February 4, 1925. Serial No. 6,842.

To all whom it may concern:

Be it known that I, CARL MERRITT CAMPBELL, a citizen of the United States, residing at Hagerstown, in the county of Washington and State of Maryland, have invented a certain new and useful Improvement in Floor Mats, of which the following is a full, clear, and exact description.

The object of this invention is to provide a floor mat having an approach that is practically proof against curling or deformation in use, without the addition of stiffeners in the approach, and in which added rigidity may be supplied at intervals throughout the mat and between the end approaches, by means of connecting rods or pintles of heavier or greater resisting quality than the other connecting rods or pintles.

The invention consists of a mat of the character described, in which each approach is composed of transversely arranged long links and short links, these links being threaded on connecting rods or pintles, preferably of U-shape, both of the limbs of one of these connecting rods or pintles engaging the long links, and only one of its limbs engaging the short links, and the other limb engaging one end of the first transverse row of links next to the approach, in addition to engaging the long links as I will proceed now to explain and finally claim.

In the accompanying drawings illustrating the invention, in the several figures of which like parts are similarly designated, Figure 1 is a top plan view of one approach and a series of body links. Fig. 2 is an edge view on the same scale as Fig. 1. Fig. 3 is an edge view, on a larger scale, of one approach and a series of succeeding links including a pair of links connected by a more rigid pinte and seen from the side opposite to that shown in Fig. 2, and showing by dotted lines how the approach is hinged and turns over under compulsion or when necessary. Fig. 4 is a side elevation of one of the longer links of the approach. Fig. 5 is a side elevation of another form of approach link of the longer type. Fig. 6 is a side elevation of the shorter links used in the approach. Fig. 7 is a side elevation of one of the intermediate links perforated to receive a pinte of ordinary size. Fig. 8 is a side elevation of the form of links that will be used in connection with the use of a pinte of larger size or gage of wire as well as with pintles of smaller size or gage.

Fig. 9 is a side elevation of a link for use in connection with the larger size or gage pinte.

The approach, shown at the right in Fig. 1 and 2, and at the left in Fig. 3 is composed of alternate groups of relatively large and small links 1 and 2, respectively. As shown particularly in Figs. 2, 3 and 4, these longer links may have their inner ends scalloped as at 3, for the usual purposes, while the other portion 4 is left plain or unscallop. Or the longer links may be without scallops as shown in Fig. 5. In either case these longer links are provided with four holes 5 arranged in pairs to receive both of the limbs of the connecting rods or pintles 6 of substantially conventional U-shape and small size, and the free ends of these rods or pintles are screwthreaded and adapted to receive nuts 7, although any other usual or approved means may be used for securing these rods or pintles in position.

The shorter links 2 have three holes 8 and 9, the holes 8 constituting a pair and being engaged by the first described pinte in connection with its engagement with the outer pair of holes in the longer links, while the holes 9 are engaged by one of the limbs of the second pinte, both limbs of the said second pinte engaging the longer links. The other limb of the second pinte engages one of a pair of holes in groups of shorter links interposed between the inner ends of the longer links and in longitudinal alignment with the larger links of the approach.

As shown in Fig. 8 and following the arrangement of Figs. 1, 2 and 3, this second transverse row of links 10 has one hole 11 of a diameter to receive a connecting rod or pinte 6 of smaller gage, while the other hole 12 is of a diameter to receive one of the limbs of a connecting rod or pinte of larger gage.

The approach is practically pivoted upon that limb of the larger gage pinte which engages the hole 12 of the link 10, so that the approach may be turned over upon the body of the mat, as indicated by dotted lines in Fig. 3.

Alternating with rows of links 10, are the links 13, shown in detail in Fig. 9, and these links are provided with larger holes 14 to receive both of the limbs of a pinte 15 of larger gage.

The next transverse row of links would be of the construction shown in Fig. 8,

while the links 16 of the rows between the rows of links 10, Fig. 8, would be of the construction shown in Fig. 7; that is to say, the links 16 are used in the body of the mat. The links 16 are perforated to receive pintles of the smaller gage of wire.

While I have shown the larger links as partly plain and partly scalloped, Figs. 1, 2, 3 and 4, and also have shown them as all plain, Fig. 5, it is obvious that these longer links may be scalloped throughout. So also the links, 2, Fig. 6, may be either plain, or scalloped in part or in whole. So also the links shown in Figs. 7, 8 and 9 may be scalloped or plain.

The links used in the construction of the approach may be of less height than the links of the body of the mat in order to provide an approach of relatively insignificant height, and thus avoid or minimize the danger of tripping the user or obstructing his progress.

The approach with practically two connecting rods or pintles forming part of its construction and with the longer links arranged on the outside, is of a rigidity that is practically immune from buckling or curling in use, and yet has the necessary flexibility for rolling up and for storage.

The body of the mat has imparted to it an increased rigidity by the use of the connecting rods or pintles of larger diameter or materials of greater rigidity.

As already indicated, leather mats as previously constructed are apt to curl or buckle on the edge, and this causes the edge to stand up from the floor with consequent danger of tripping to pedestrians. The kicking of feet against the edge may cause the wires composing the pintles to bend upwardly, thus causing the mat to stand up away from the floor.

As is well known, leather is porous, and a mat constructed from it is subject to curling or buckling when exposed to varying degrees of moisture due to expansion and contraction of the leather.

These conditions are counteracted by the use of the heavier U-shaped connecting rods or pintles inserted instead of the regular lighter wire pintles at intervals of approximately twenty inches throughout the mat. Where a single stiffener rod is used in conjunction with the ordinary small gage wire U-shaped pintles, they are passed through the center of the links between the limbs of the pintles and therefore a considerable part of the links must be cut away to allow for their passage, with the result that the links are weakened. In my invention the link-connecting pintles of larger gage wire are used in the manner and for the same purpose as pintles of smaller gage wire, and the diameter of the ends of the links is enlarged sufficiently to allow for the increased

size of the pintles, so that the mat has a relatively greater strength than one which does not include the larger pintles. It is obvious that the U-shaped large pintles possess at least double the strength of the single rod, and in addition both limbs of the pinte pass through the mat and in close proximity.

Because of the facts stated, it is essential that the approaches be reinforced and given greater strength, and this is accomplished in the approaches of this invention. The solid end construction offers the required amount of resistance to curling and buckling. It is impractical to insert heavy rods and yet retain the much desired approach of lower level than the body of the mat and thereby reduce the likelihood of pedestrians stumbling. In my construction the links of the approach are thin in vertical dimension as compared with the links of approaches of common construction, and thinner than the intermediate links of the mat.

Another advantage of this approach is the removal of the hinge to a relatively long distance from the end of the mat, as indicated by the dotted lines in Fig. 3. It is obvious that the farther this hinge is removed from the end, the less the likelihood of the approach being kicked up, and thus offering an obstruction for pedestrians.

Still another advantage of this extra solid approach is its wearing quality. The approach receives the hardest usage of the entire mat, and in many cases is the first portion to wear out. The present approach will outlast the rest of the mat, and the smooth unbroken edge will always present a pleasing appearance.

The common method of fastening the ends of the pintles is by bending them together and soldering them or fastening with a metal clip, or otherwise. Experience has shown that these ends, thus fastened, often become loosened through hard usage, and thus allow the mat to come apart. Instead of using this mode of fastening, I screw-thread the ends of the pintles and apply thereto metal nuts, the ends of the pintles extending slightly beyond the nuts and these ends spread or upset over the nuts (see Fig. 1) so as to prevent the nuts from coming off, thereby insuring a permanent fastening which is not likely to work loose.

The heavier pintles may be used at any desired points in the mat and in any desired number, and some or all of the pintles may be secured by screwthreads and nuts, or some by screwthreads and nuts and others by any other usual or approved securing means.

Other variations in the details of construction are permissible within the principle of the invention and the scope of the claims following.

What I claim is:—

1. A floor mat, having an approach composed of alternating groups of relatively large and small links of relative thinness in vertical dimension, the large links pierced transversely with four holes and the small links pierced transversely with three holes, the groups of links being fastened together by two adjacent U-shaped pintles, the large links engaged by both limbs of both pintles and the small links by both limbs of one of the pintles and by one of the limbs of the other pinte.
2. A floor mat, having an approach composed of groups of links of relative thinness in vertical dimension and pierced transversely and fastened together by two ad-

20 jacent U-shaped pintles, the links being in alternating groups of links of different length, there being longer links on the outside, the longer links having four holes each to receive the limbs of both of the pintles and the alternating groups of shorter links having three holes to receive both of the 25 limbs of the outermost pinte and one of the limbs of the innermost pinte.

In testimony whereof I have hereunto set my hand this 3rd day of February A. D. 1925.

CARL MERRITT CAMPBELL.
